UNITED STATES PATENT OFFICE.

WILLIAM FAIRBAIRN, OF CALABOGIE, CANADA.

ENVELOP-OPENER.

SPECIFICATION forming part of Letters Patent No. 586,170, dated July 18, 1897.

Application filed April 17, 1897. Serial No. 632,595. (No model.)

To all whom it may concern:

Be it known that I, WILLIAM FAIRBAIRN, a citizen of the United States, residing at Calabogie, in the Province of Ontario and Dominion of Canada, have invented certain new and useful Improvements in Envelop-Openers; and I do hereby declare the following to be a full, clear, and exact description of the invention, such as will enable others skilled in the art to which it appertains to make and use the same.

My invention relates to envelop-openers.

My object is to provide an envelop-opener of extremely simple and cheap construction, whereby opening may be had quickly and easily and in such an improved manner that the edges of the open portion will be spread apart or flared, so that the letter-sheet in the envelop may be more readily removed.

20 The invention is to be adapted for use in connection with pencils, penholders, watch-charms, &c.

The foregoing object is accomplished by the provision of an envelop-opener of improved construction, and more particularly by employing a knife of peculiar construction, as will appear more fully hereinafter.

In the accompanying drawings, Figure 1 is an enlarged detail view in sectional elevation, 30 disclosing the manner of using the device; Fig. 2, a cross-section of an envelop after being cut by my opener; Fig. 3, a view looking toward the grooves and knife; Fig. 4, a cross-section showing the peculiar shape of knife, and Fig. 5 a view showing the device applied to a pencil.

The body of the opener is shown at 1, the same being provided with a longitudinally-extending groove 2, which is flared or widened 40 at its mouth 3, so as to permit of the easy insertion of the envelop. Formed integral with the body or connected thereto in any suitable manner is a knife 4, of improved construction. It will be observed that when the groove 2 reaches the knife it is formed into the branches 5 and 6, which lie on opposite sides of said knife, said branches being quite narrow and diverged from each other. The knife being located between these branches and 50 having its sides forming walls thereof is substantially triangular in cross-section. Said

knife is formed with a sharp upper edge 7, and it is provided with a pointed needle-like projection 8, which is undercut at 9, so that the said needle lies in the middle of the groove 55 2, in a position to enter between the flap of the envelop and the body thereof. The peculiar disposition of the branch grooves 5 and 6, in connection with the knife having the needle-point and substantially triangular in 60 cross-section, constitute very important parts of the present device. It will be observed that as a consequence of said construction the portions of the flap and body of the envelop will be spread apart when being cut, so that 65 after the cutting operation has been completed the letter-sheet can be withdrawn from the envelop with ease. The manner in which the edges of the envelop are flared by the knife is clearly shown in Fig. 2, the flared edges 70 being disclosed at 10 and 11.

In Fig. 5 the device is shown applied to a pencil and constitutes a part of the tip thereof, which is shown at 12. In this tip there may be inserted an eraser 13, and the parts 75 14 and 15 constitute diametrically disposed wings, each of which is an opener constructed in accordance with my invention. Of course the device is applicable to penholders and other articles of like character, or it can be 80 used by itself and made in the shape of a paper-weight.

The manner of opening the envelop will be seen from an inspection of Fig. 1, where the envelop is shown at 16, an end flap being 85 shown at 17 and a sealing-flap at 18. The envelop is introduced into the flared portion of the groove 2 and is then slid along in said groove, or the device itself is slid in relation to the envelop, the needle-point passing between the flap and beginning to cut, and immediately after the cut portion passes through the branch grooves, which, by their inclination, spread or flare the edges, so that after the cutting operation has been finished the 95 letter-sheet may be readily removed.

I lay no claim, broadly, to the construction of my device, as the patent to Jones, No. 299,398, discloses an envelop-opener, and my improvement over the same resides in the 100 novel form of knife in connection with the branching grooves at the sides thereof.

Having thus described my invention, what I claim as new, and desire to secure by Letters Patent, is—

1. In an envelop-opener, the combination with a body having a groove for the envelop, of a cutting-knife located in the groove and having inclined sides which are separated from the body by inclined diverging branch grooves.
2. In an envelop-opener, the combination with a body having a groove for the envelop, of a cutting-knife located in the groove and substantially triangular in cross-section, said

knife having inclined sides which converge to an apex and provided with an undercut 15 needle-point lying in the main groove, the sides of the cutting-knife being separated from the body by inclined diverging grooves that lead into the main groove.

In testimony whereof I have signed this 2c specification in the presence of two subscribing witnesses.

WILLIAM FAIRBAIRN.
